UNITED STATES PATENT OFFICE

150,829

DESIGN FOR A TUBE AND TOOTHBRUSH
HOLDER

Joseph W. Doucette, Waltham, Mass.

Application December 19, 1945, Serial No. 124,854

Term of patent 14 years

(Cl. D4—3)

To all whom it may concern:

Be it known that I, Joseph W. Doucette, a citizen of the United States, residing at Waltham, in the county of Middlesex and State of Massachusetts, have invented a new, original, and ornamental Design for Tube and Toothbrush Holder, of which the following is a specification, reference being had to the accompanying drawing, forming part thereof.

Figure 1 is a side elevational view of a tube and toothbrush holder showing my new design.

Figure 2 is a front elevational view thereof, and Figure 3 is a top plan view of the holder.

I claim:

The ornamental design for a tube and toothbrush holder, as shown.

JOSEPH W. DOUCETTE.
